UNITED STATES PATENT OFFICE.

ALFRED C. JOHNSON, OF WINTERS, CALIFORNIA.

TRANSMISSION.

1,182,490.

Specification of Letters Patent. Patented May 9, 1916.

Application filed May 25, 1915. Serial No. 30,326.

To all whom it may concern:

Be it known that I, ALFRED C. JOHNSON, a citizen of the United States, residing at Winters, in the county of Yolo and State of California, have invented new and useful Improvements in Transmission, of which the following is a specification.

This invention relates to a transmission particularly designed for use on traction engines.

One of the objects of the invention is to provide a simple, compact transmission of the character described, in which power is transmitted from a single drive-shaft to a sectional jack shaft, and which is provided with means for transmitting power to either or both shafts in either direction.

Further objects will hereinafter appear.

The invention consists of the parts and the construction and combination of parts as hereinafter more fully described and claimed, having reference to the accompanying drawings, in which—

Figure 1 is a plan view of a tractor, showing the application of the invention. Fig. 2 is a central longitudinal section of one of the reversing gears.

A indicates the main frame of a tractor, on which is supported an engine 2. The tractor may be provided with a suitable form of steering wheel 3 and a pair of traction wheels 4. Directly connected with the main engine clutch 5 is a driving shaft 6 which extends through the transmission case 7. Mounted on the shaft, interiorly of the transmission case, is a pair of reversing gears 8 and 9, and connected with each reversing gear and adapted to be driven in one direction or the other by same is a pair 40 of driving pinions 10 and 11.

Disposed at right angles with relation to the main driving shaft 6, and journaled in the transmission case, as at 12 and 13, is a pair of jack-shafts 14 and 15. Mounted on the inner end of shaft 14 is a beveled gear 16 which constantly intermeshes with the pinion 10, and secured on the inner end of shaft 15 and intermeshing with pinion 11 is a beveled gear 17. Secured on the outer end 50 of each shaft 14 and 15 is a spur pinion 18 which is adapted to intermesh with either an external or an internal gear 19 secured on the main traction wheels.

The reversing gears 8 and 9 may be of the standard type such as are used on marine engines. The clutches indicated at 26 and

27 permit the connected pinions to revolve in unison with the shaft to be turned in a reverse direction to same or to remain free while the shaft is running. This is accomplished as follows: Referring to Fig. 2, 20 indicates the main casing of the reversing gear. Journaled interiorly of said casing is a plurality of intermediate beveled pinions 21 which intermesh with beveled gears 22 and 23. Gear 22 is mounted on a sleeve which is secured on the drive-shaft by a key or like means, while gear 23 is mounted on a sleeve 24 which is loosely mounted on the driving shaft. The driving pinion 10 is secured on the sleeve 24 and it will, therefore, revolve in unison with the sleeve and gear 23. Slidably mounted on sleeve 25, which is secured to the shaft and upon which the beveled gear 22 is mounted, is a 75 clutch 26 which is adapted to be thrown into and out of engagement with an internal clutch face 27 formed on the main casing 20. Clutch 26 is normally thrown into engagement with the clutch 27 of the main 80 casing 20 by a spring 28, causing the two sections of the reversing gear to revolve in unison. As the clutch section 26 is slidably mounted by a feather and key on the sleeve 25, which is keyed rigidly on the driving 85 shaft, a direct driving connection will be formed between the shaft and driving pinion 10. A direct drive is thus normally transmitted through the reversing gear from shaft 6 to the driving pinion 10. This 90 operation is true of both reversing gears as they are similar in construction. If it is desired to release one of the reversing gears to permit the adjacent or connected wheel to turn freely while the wheel on the opposite side is being driven in one direction or the other, it is only necessary to throw out clutch 26 sufficiently far to bring the clutch faces out of engagement. No power will 95 then be transmitted as the casing 20, together with the intermediate pinions 21, will run freely about the beveled gear 23. If it is desired to transmit a reverse movement to the driving pinion it is necessary to first move clutch 26 into position where the clutch faces are out of engagement and then to tighten the brake band 30 to lock the casing 20 against revolving movement. Power will then be transmitted from the 100 main driving shaft to the beveled gear 22 and will then be transmitted through the intermediate pinions 21 to the beveled gear 105 110.

23, with connected sleeve 24, and driving pinion 10, causing these to revolve in the opposite direction. A reverse movement may be transmitted to either or both traction wheels or a direct drive may be transmitted to one and a reverse drive to the other, thus permitting the tractor to turn in a very small space. Again, either or both of the driving connections may be thrown out by releasing the clutches 26 and the reversing gears or by throwing out the main engine clutch 5. The clutch section 26 of each reversing gear is preferably operated by a lever 31 and the movement of this lever is also transmitted in the usual manner to release or tighten the brake band 30 by means of the cam 32 and connecting link 33.

By referring to Fig. 1, it will be seen that shafts 14 and 15 are offset with relation to each other. This permits a direct drive to be transmitted to both or either of the shafts from the main driving shaft, the speed ratio of which is equal. This construction permits a compact narrow transmission case and also reduces the number of bearings which would otherwise be required. A tractor of narrow tread can thus be constructed to the wheels of which power is transmitted with the least possible loss of efficiency through friction, and which can be easily handled and driven in one direction or the other, as the driving connections permit both or either wheel to run freely to reverse in unison or independently of each other, or to drive ahead in unison or independently of each other. A flexible drive and control is thus produced.

While a transmission case provided with two or more speeds has not been shown in the present case, it is obvious that same may be interposed between the main engine clutch and the driving shaft 6, thus permitting the tractor to be driven at different speeds without altering the engine speed. While the driving pinions 18 are here shown as connected with traction wheels, it is obvious that they may be connected with the driving sprocket of a self-laying track tractor and that they may be used for other purposes not here specified.

Having thus described my invention, what I claim and desire to secure by Letters Patent is—

1. In a traction engine, a drive shaft, a pair of driven shafts offset with relation to each other, means for transmitting power from the drive shaft to either driven shaft in either direction, means for transmitting a reverse movement to the driven shafts in unison or ahead movement in unison, a pair of traction wheels, and means for transmitting power from the driven shafts to each adjacent traction wheel.

2. In a traction engine, a drive shaft, a pair of driven shafts offset with relation to

each other, a gear on the inner end of each driven shaft, a pair of pinion gears loosely mounted on the drive shaft intermeshing with the driven shaft gears, one with each gear, means for locking one or both of the pinion gears to rotate in unison with the drive shaft, a pair of traction wheels, and means for transmitting power from the driven shafts to each adjacent traction wheel. 75

3. In a traction engine, a drive shaft, a pair of driven shafts offset with relation to each other, a gear on the inner end of each driven shaft, a pair of pinion gears loosely mounted on the drive shaft intermeshing with the driven shaft gears, one with each gear, a clutch mechanism connected with each pinion gear for locking or releasing same with relation to the drive shaft, a pair of traction wheels, and means for transmitting power from the driven shafts to each adjacent traction wheel. 85

4. In a traction engine, a drive shaft, a pair of driven shafts offset with relation to each other, a gear on the inner end of each driven shaft, a pair of pinion gears loosely mounted on the drive shaft intermeshing with the driven shaft gears, one with each gear, a reversing gear connected with each driving pinion, a pair of traction wheels, and means for transmitting power from the driven shafts to each adjacent traction wheel. 90

5. In a traction engine, a drive shaft, a pair of driven shafts offset with relation to each other, a gear on the inner end of each driven shaft, a pair of pinion gears loosely mounted on the drive shaft intermeshing with the driven shaft gears, one with each gear, a reversing gear connected with each driving pinion, means for locking each reversing gear and driving pinion to revolve with the drive shaft, a pair of traction wheels, and means for transmitting power from the driven shafts to each adjacent traction wheel. 100

6. In a traction engine, a drive shaft, a pair of driven shafts offset with relation to each other, a gear on the inner end of each driven shaft, a pair of pinion gears loosely mounted on the drive shaft intermeshing with the driven shaft gears, one with each gear, a reversing gear connected with each driving pinion, independent means connected with each reversing gear and driving pinion for locking same to revolve in unison with the driving shaft, a pair of traction wheels, and means for transmitting power from the driven shafts to each adjacent traction wheel. 115

7. In a traction engine, a drive shaft, a pair of driven shafts offset with relation to each other, a gear on the inner end of each driven shaft, a pair of pinion gears loosely mounted on the drive shaft intermeshing 120

- with the driven shaft gears, one with each gear, a reversing gear connected with each driving pinion, means for transmitting power from the drive shaft to each reversing gear to revolve the driving pinions in a reverse direction to the drive shaft, a pair of traction wheels, and means for transmitting power from the driven shafts to each adjacent traction wheel.
- 5 10 8. In a traction engine, a central longitudinally extending drive shaft, a pair of driven shafts, means for transmitting power from the drive shaft to either
- driven shaft in either direction, means for transmitting a reverse movement to the 15 driven shafts in unison or ahead in unison, a pair of traction wheels, and means for transmitting power from the driven shafts to each adjacent traction wheel.
- In testimony whereof I have hereunto set 20 my hand in the presence of two subscribing witnesses.

ALFRED C. JOHNSON.
